DESIGN FOR A MOTOR VEHICLE BUMPER GUARD

Alexander C. de Hoffmann, New York, N. Y.

Application October 27, 1939, Serial No. 87,884

Term of patent 14 years

To all whom it may concern:

Be it known that I, Alexander C. de Hoffmann, a citizen of the United States, residing in New York, in the county of Bronx and State of New York, have invented a new, original, and ornamental Design for a Motor Vehicle Bumper Guard, of which the following is a specification, reference being had to the accompanying drawing, forming part thereof.

Figure 1 is a side elevational view of a motor vehicle bumper guard, showing my new design.

Figure 2 is a front elevational view,

Figure 3 is a rear elevational view, and

Figure 4 is a top plan view of the same.

I claim:

The ornamental design for a motor vehicle bumper guard, as shown.

ALEXANDER C. DE HOFFMANN.
